(57) **CLAIM**

The ornamental design for a quilted zippered storage bag, as shown and described.

DESCRIPTION

FIG. 1 is a perspective view of a quilted zippered storage bag;

FIG. 2 is right side view of the quilted zippered storage bag;

FIG. 3 is a left side view of the quilted zippered storage bag;

FIG. 4 is a top view of the quilted zippered storage bag;

FIG. 5 is a bottom view of quilted zippered storage bag;

FIG. 6 is a front view of the quilted zippered storage bag; and,

FIG. 7 is a rear view of the quilted zippered storage bag. The broken lines of FIGS. 1-7 illustrate stitching which forms a part of the claimed design.

1 Claim, 6 Drawing Sheets
